(57) **CLAIM**

The ornamental design for a cosmetic container, as shown and described.

DESCRIPTION

FIG. 1 is a perspective view of a cosmetic container showing my new design;

FIG. 2 is a front elevational view thereof where a rear elevational view, and left and right side views thereof are respectively identical to the front elevational view of FIG. 2; FIG. 3 is a top plan view thereof;

FIG. 4 is a bottom plan view thereof; and,

FIG. 5 is a cross-sectional view thereof, taken along line 5-5 in FIG. 3.

The broken lines in the figures illustrate the portions of the design that form no part of the claimed design.

1 Claim, 4 Drawing Sheets
